DES. 2037

Isaac De Touché, of Cincinnati, Ohio.

Assignee to

Bridge Beach Co. of St. Louis, Mo.

Letter Patent No. 2037 Dated March 16, 1865.

Design for a Stave Ornament.

Specification referred to in these Letters Patent and making part of the same.

In allusion it may concern.

Be it known that Isaac De Touché, of the City of Cincinnati and County of Hamilton in the State of Ohio, have invented or produced a new and original Design for the Ornament of Box Staves; and I do hereby declare that the following is a full and exact description of the same, reference being had to the accompanying photographic drawing, and to the letters of reference marked thereon, making a part of this specification, in which the ornament is shown in a modified form of the "Fleur de lis."

A. A. A. A. represents leaves falling gracefully over on either side. B represents a seed vessel showing two rows of seeds. C is the neck moulding, representing a rope, binding the whole together.

Having thus described my design for the ornament of Box Staves what I claim as new therein, and desire to secure by Letters Patent is

The configuration and Design of Ornament as modified Fleur de lis, and as applied to the ornamentation of Box Staves, as herein described, and shown in the accompanying photographic drawing.
